UNITED STATES PATENT OFFICE.

AUGUST MEYER, OF HICKSVILLE, NEW YORK, ASSIGNOR OF ONE-HALF TO WILLIAM A. KIELMANN, OF HICKSVILLE, NEW YORK.

ROOFING STRUCTURE.

Application filed January 12, 1922. Serial No. 528,664.

To all whom it may concern:

Be it known that I, AUGUST MEYER, a citizen of the Republic of Germany, and resident of Hicksville, in the county of Nassau 5 and State of New York, have invented certain new and useful Improvements in Roofing Structures, of which the following is a specification.

The principal object of this invention is 10 to provide a roof covering which will be very durable and will withstand the erosive action of the elements for generations.

Another object is to provide a roofing which can be applied to a building without 15 the use of any metal or other similar fastening devices but which is merely laid upon lathing or other wooden strips without requiring any special mechanical skill.

Another object is to produce a roofing 20 structure which will be leak proof, and a further object is to produce a roofing structure the constituent elements of which can be made of ordinary brick clay or other argillaceous material and thus can not only 25 be manufactured at a very low cost, but will also be fireproof and will not curl up at the edges.

For the accomplishment of these and such 30 further objects as will hereinafter be apparent to those skilled in the art to which this appertains, the invention consists in the construction, combination and arrangement of parts herein specifically described and 35 illustrated in the accompanying drawings wherein is shown a preferred embodiment of the invention, but it is to be understood that changes, variations and modifications 40 may be resorted to which fall within the scope of the claim hereunto appended.

In the drawings forming a portion of this specification:

Fig. 1 is a perspective view of a section 45 of a roof covered with a roofing covering constructed in accordance with my invention.

Fig. 2 is a section taken along the line 2-2 of Fig. 1.

Fig. 3 is a section on the line 3-3 of Fig. 2.

Fig. 4 is a perspective similar to Fig. 1 50 of a modified form.

Fig. 5 is a perspective of one of the elements used in carrying out my invention and

Fig. 6 is a perspective of a cooperating 55 element.

Referring to the drawings, the numerals

10 indicate any suitable strips such as laths or purlins which are nailed at suitable intervals and extend transversely across the rafters of the building to be roofed. A series of cooperating tile elements 11 and 12 60 which preferably are constructed of ordinary brick clay or any other argillaceous substance are provided with downwardly projecting lugs 13 and 14 respectively, which lugs are adapted to engage over the purlin 65 10 to prevent the tiles from sliding downwardly off the roof. In the modification shown in Fig. 1 two different sizes of cooperating tiles are used, the wider one 11, being cut away adjacent its sides to provide 70 the tapering surfaces 15 and a central projecting rib 16, while the narrower tile 12 is similarly cut away to provide the tapering surfaces 17 and a narrow central projecting rib 18. In laying the tiles the narrower tile 75 12 is first placed upon the roof with the lug 14 engaging over the lowermost purlin 10, and the wider tile 11 is placed alongside the tile 12 with the tapered surfaces 15 above and in engagement with the tapered surfaces 17.

It will be noted that the dimensions of the 80 tapered surfaces 15 and 17 are equal so that the edges or sides of the adjacent tiles will be in contact with the central ribs 16 85 and 18 and that the thickness of the tiles at the tapered portions are the same so that the upper or outer exposed surfaces of the tiles in each respective row will all lie in a common plane. After the tiles in the 90 lower row have been placed upon the roof the next row of tiles is laid in a similar manner, the purlins 10 being spaced apart so that the upper row will overlap a portion of the tiles in the next lower row, the spacing 95 of the purlins preferably being such that the upper tile overlies substantially half of the lower tile. I have found from experience that it is not necessary to employ any fastening means such as nails, screws or the like to 100 hold the tiles in place as the weight of the tiles and particularly the effect of the pressure of each succeeding upper row of tiles upon the lower tile effectually prevents the tiles from becoming loosened or raised by 105 the wind. Furthermore, by constructing the tiles of argillaceous material they do not become warped or curl up on the edges and are entirely fireproof.

If desired instead of constructing the tiles 110

of two different widths as shown in Figs. 1 to 3, 5 and 6, they all may be made with the same transverse cross sectional dimensions as the wider tiles 11 and with the lugs 13 projecting from different sides of the tiles so that the ribs 16 may be placed alternately upward or downward as shown in Fig. 4.

It will further be noted that when the tiles are placed in position upon the roof, 10 the tapered surfaces 15 and 17 extend upwardly away from the junction between the adjacent tiles so that any water which might seep through the space between the abutting sides of the tile would be prevented 15 from leaking through the roof.

Having thus described my invention what I claim as new and desire to secure by Letters Patent of the United States is:

A roofing structure comprised of a plurality of cooperating pairs of elements, each 20 of said elements being provided with a cen-

tral projecting rib extending longitudinally the full length of the element, a reduced portion extending alongside of and projecting laterally from said rib, and a downwardly projecting lug adapted to be engaged over a purlin to hold said elements in position, said reduced portions having one of the faces thereof inclined, and said central rib and inclined faces of the respective members of each pair of elements facing in opposite directions and being so proportioned that said elements may be arranged in substantially horizontally extending series with the longitudinally extending edges of said ribs 25 and reduced portions in contacting engagement, whereby the outer surfaces of said elements will be in a common plane.

Signed at New York, in the county of New York and State of New York, this 23rd day of December A. D. 1921.

AUGUST MEYER.
